GEORGE A. KEENE, OF BOSTON, MASSACHUSETTS, ASSIGNOR TO HIMSELF
AND JOSEPH E. MANNING, OF SAME PLACE

Letters Patent No. 63,164, dated March 26, 1867.

IMPROVEMENT IN NECK-TIES.

The Schedule referred to in these Letters Patent and making part of the same.

TO ALL WHOM IT MAY CONCERN:

Be it known that I, GEORGE A. KEENE, of Boston, in the county of Suffolk, and State of Massachusetts, have invented a new and useful Paper Neck-Tie; and I do hereby declare that the following is a full, clear, and exact description of the construction and operation of the same, reference being had to the accompanying drawings, forming a part of this specification, in which—

Figure 1 is a front elevation.

Figure 2 is a longitudinal cross-section.

Figure 3 is an elevation of the clinch-bar and elastic ring; and

Figure 4, a vertical cross-section.

In the manufacture of paper neck-ties as improved by me, I form the bow from a single straight strip of paper, either of uniform color plainly embossed, or embossed or printed in patterns of any desirable color or character, as shown at A, figs. 1, 2, and 4. Around the centre of this bow, when folded, I place a band, B, plain or suitably embossed or printed, and punch holes in the ends thereof, and through one, two, or three thicknesses of the bow at its centre, when folded and near the bottom of wing-piece C, to allow of the passage of a rubber loop. These holes are shown at h, figs. 2 and 4. I then take the clinch-bar e, shown at fig. 3, place upon it the elastic ring d, pass said ring through holes h and press the ends f f' of the clinch-bar e through the tie-strip A, the knot-band and the wing-piece upsetting their ends and fastening all firmly together. Instead of fastening by the clinch-bar e, an eyelet may be used, though not with as good advantage, and in lieu of the folded bow-piece A, a single piece with ends of any desirable shape or ornament, crossed by the knot-band, may be used, put together in the same way by the clinch-bar, thus simulating the square knot, "granny knot," or "sailor's knot," or the "fountain tie."

I disclaim the form and arrangement of metallic clasps shown by Elias Childs in his patent of May 22, A. D. 1866, and also the method of attaching the elastic loop used by him, and the employment of any other elastic loop save an unbroken ring, for this only do I consider advantageous and cheap when employed with my device; and

I claim as my invention, and desire to secure by Letters Patent—

Fastening wing-piece, knot-band, and tie-strip together, and attaching the elastic ring by means of the clinch-bar, as shown, illustrated, and described.

GEO. A. KEENE.
